UNITED STATES PATENT OFFICE.

JOHN S. WORTH, OF COATESVILLE, PENNSYLVANIA, ASSIGNOR TO HIMSELF AND
WILLIAM P. WORTH, OF COATESVILLE, PENNSYLVANIA.

ROLLING-MILL.

1,206,637.

Specification of Letters Patent. Patented Nov. 28, 1916.

Application filed September 28, 1915. Serial No. 53,095.

To all whom it may concern:

Be it known that I, JOHN S. WORTH, a citizen of the United States, and a resident of Coatesville, county of Chester, State of Pennsylvania, have invented certain Improvements in Rolling-Mills, of which the following is a specification.

My invention relates to certain improvements in means for driving the rolls of a rolling mill.

One object of my invention is to construct the mill so that each of the rolls is independently driven.

A further object of the invention is to eliminate the gearing which is universally located between the rolls and the power.

A still further object of the invention is to dispense with frequent dressing and sizing of the rolls and to improve the product by obliterating the infinitesimal waves usually found in plates, which are due to the lost motion in the gearing.

In the accompanying drawings: Figure 1 is a front elevation of a rolling mill, illustrating my invention and showing the supporting rolls and the intermediate roll driven independently; Fig. 2 illustrates a rolling mill in which the working rolls are driven independently from opposite sides; Fig. 3 is a view illustrating my improved independent drive in connection with a 3-high rolling mill, and Fig. 4 is a view illustrating my improved independent drive in connection with a 2-high rolling mill.

Referring to the drawings, 1 is the lower working roll. 2 is the upper working roll. 3 is the intermediate roll. 4 is the lower supporting roll and 5 is the upper supporting roll. These rolls are mounted in housings 6 in the ordinary manner and the pressure is regulated by the set screws 7 at the upper ends of the housings.

In the present instance, I have illustrated horizontal steam engines as the driving power, but it will be understood that electric motors, or other types of engines, may be used without departing from the essential features of the invention.

8 is an engine having a crank shaft 11, which is connected to the lower supporting roll 4, Fig. 1, by a coupling shaft 12. The coupling 12^a is of the ordinary flexible type and the coupling 12^b is similar to the coupling 12^a, with the exception that the socket

is flanged so that it can be secured to the 55 flange on the end of the shaft 11.

9 is an engine having a crank shaft 14, which is connected to the upper supporting roll 5 by a coupling shaft 15 and couplings 15^a and 15^b.

10 is an engine having a crank shaft 16 connected to the intermediate roll 3 by the coupling shaft 17 and couplings 17^a and 17^b. The couplings shown allow for the free vertical movement of the rolls.

The working rolls 1 and 2 by the above arrangement are frictionally driven from the supporting rolls 4 and 5 respectively. These rolls are independently driven from the engines as above set forth.

In Fig. 2, I have shown the two working rolls 1^a and 2^a connected directly to the shafts 11^a and 14^a of their respective engines, one on each side of the set of rolls in the present instance. The intermediate roll, 75 in this instance, is not independently driven.

In Fig. 3, I have illustrated a 3-high mill in which the lower roll 1^b is driven directly from the crank shaft 11^b and the upper roll 2^b is driven directly from the crank shaft 14^b. In this case, also, the intermediate roll is not independently driven. In a 2-high mill the intermediate roll is dispensed with and the plate is rolled between the upper and the lower rolls, see Fig. 4. In this case, 85 I have illustrated electric motors 9^a and 10^a as substitutes for the reciprocating engines shown in Fig. 1. The motor 9^a is connected to the lower working roll 1^c by a coupling shaft 11^c and the motor 10^a is connected to 90 the upper working roll 2^c by the shaft 14^c. Each of these shafts has flexible couplings and each motor shaft is provided with a fly wheel, as shown.

By the above arrangement I dispense with 85 the use of stands of gearing which are now universally used in rolling mill practice for rolling plates and other products and, in the present method of driving through gearing, the rolls must bear about the same proportion to each other that the gears bear which drive them, consequently, frequent dressing and sizing of the rolls is necessary or there will be a breakage of the gears, as well as an unsatisfactory product.

By the use of the independent driving mechanism, I am enabled to keep the surface speed of the driven rolls practically

the same, irrespective of their relative diameters.

While I have shown the power units in the form of steam engines, it will be understood that other power mechanism may be used, such as motors of different types.

In Fig. 1, the cylinders 8 and 9 may be the high and low pressure cylinders of a compound engine, one cylinder being used for driving one of the rolls and the other cylinder can be used to drive the other roll.

The construction in which the working rolls are independently driven is claimed in a separate application filed as a division on the 6th day of July, 1916, under Serial No. 107,810.

I claim:—

1. A rolling mill having a plurality of rolls; and means for independently driving a plurality of said rolls.

2. The combination in a rolling mill, of two working rolls and an intermediate roll; and independent means for driving each of said working rolls and for driving the intermediate roll.

3. The combination in a rolling mill, of two working rolls; a supporting roll back of each working roll; an intermediate roll; and means for directly driving each supporting roll independently.

4. The combination in a rolling mill, of two working rolls and an intermediate roll; a supporting roll back of each working roll; independent means for directly driving each of said supporting rolls; and independent means for driving the intermediate roll, said working rolls being driven by their supporting rolls.

JOHN S. WORTH.
